(57) **CLAIM**

The ornamental design for a ceiling mounted sign, as shown and described.

DESCRIPTION

FIG. 1 is a front perspective view of a ceiling mounted sign illustrating the new design.

FIG. 2 shows a top perspective view of the ceiling mounted sign illustrated in FIG. 1.

FIG. 3 shows a front view of the ceiling mounted sign illustrated in FIG. 1.

FIG. 4 shows a top view of the ceiling mounted sign illustrated in FIG. 1.

FIG. 5 shows a left side view of the ceiling mounted sign illustrated in FIG. 1; and,

FIG. 6 shows a right side view of the ceiling mounted sign illustrated in FIG. 1.

The broken line showing of elements on the ceiling mounted sign illustrate portions of the article that form no part of the claimed design.

1 Claim, 6 Drawing Sheets
